UNITED STATES PATENT OFFICE

PAUL M. MARKO, OF BROOKLYN, NEW YORK, ASSIGNOR TO WILLARD STORAGE BATTERY COMPANY, OF CLEVELAND, OHIO, A CORPORATION OF WEST VIRGINIA

RADIO BATTERY CONSTRUCTION

Application filed July 5, 1924. Serial No. 724,333.

This invention relates to a radio battery construction. An object of the invention is to provide a simple, efficient and durable closure construction for radio batteries whereby the battery can be very quickly and easily closed and opened and yet when closed the parts are so related as to form a very simple and tight joint to prevent leakage or splashing.

10 Another object of the invention is to provide a combination and arrangement of parts which are extremely simple in their construction and assembly so that the battery can be manufactured at a very low cost and yet be very strong and durable.

This invention is an improvement over the radio battery construction shown in my patent No. 1,485,282 issued February 26, 1924.

20 The invention is illustrated in the drawings, of which—

Figure 1 is a sectional view of the upper end of a battery showing the closure construction;

25 Fig. 2 is a plan view of the battery;

Fig. 3 is a sectional view through one form of closure cap;

Fig. 4 is a sectional view through the upper end of another form of closure construction;

30 Fig. 5 is a sectional view through a form of closure cap;

Fig. 6 is a plan view of the cap shown in Fig. 5; and

35 Fig. 7 is a sectional view through a still further form of closure cap.

The forms of the invention shown in the drawings are preferred forms, although it is understood that modifications in the construction and arrangement of the parts and in the character of the materials used may be adapted without departing from the spirit of the invention as set forth in the appended claims.

40 In its general aspect the invention contemplates the provision of a plurality of parts to form the closure for the container of a radio battery, which will be few in number and yet so efficiently related as to form a strong and durable type of closure

capable of being manufactured at an extremely low cost.

To this end I provide a cap portion of some pliable material such as soft rubber which is disposed across the top of the container and provided with passages through which the terminals of the electrodes to a battery extend. This cap is held in place by a ring which embraces the end of the container, said ring being provided with means 55 for engaging the top of the cap around its periphery to hold the cap firmly in place on top of the container.

The invention further contemplates the combination with the cap of soft pliable material such as rubber, of a layer of stiffer material such as hard rubber, which may be connected thereto in any suitable manner such as by vulcanization. This reinforcement is intended for the purpose of preventing the pliable cap from sagging or bending under the weight of the parts connected thereto whenever the container is of considerable size.

50 The invention still further contemplates 75 the provision of certain forms of the cap with dependent flanges which are adapted to nest snugly against the inner walls of the container at its upper end so as to further enhance the tight joint formed between the 80 cap and the container.

The invention also contemplates the provision of some forms of the cap with a recess on the under surface adjacent the area where the ends of the electrodes extend 85 through the cap, in order to insure that no leakage of the liquid occurs.

In the preferred forms of the invention as shown in the drawings, I provide a container 1, which is preferably of glass, the 90 upper end of which is provided with threads 2 adopted to be engaged by a sleeve or ring or cover member 3, this ring being provided with a flange 4 which extends inwardly a short distance sufficient to extend over the 95 upper edge of the cap. This flange is adapted, as the ring 3 engages with the upper end of the container 1, to bear on the periphery of a closure cap 5. This closure cap is preferably made of any suitable 100

pliable material such as soft rubber, although, of course, it may be made of hard rubber. This cap is provided with nipples such as 6, preferably formed integral with the cap and of substantial height compared to their width. These nipples are pierced to permit the passage therethrough of the upper ends 7 and 8 of the electrodes of the battery.

In some forms of the cap I provide a dependent flange such as 9 which fits snugly within and against the inner walls of the container 1 so as to further insure a tight joint between the cap and the container. In certain forms of the cap I also provide a recess 10 cut out of the under surface of the cap so that liquid which may be formed on the upper ends of the electrodes will have a longer path to travel to get out through the joint than otherwise, and in this respect the liability of leakage is further reduced. The cap 5 is provided with a filling aperture 11 and a vent hole 12.

In another form of the invention, shown in Fig. 4, the container 13 is provided with threads 14 engageable with a ring 15 having an inwardly extending flange 16 adapted to bear on the periphery of a cap 17, preferably of soft rubber. This cap, however, is provided with a reenforcing layer 18 of, preferably, stiffer material, such as hard rubber, which is preferably vulcanized thereto. This cap 17 is also provided with nipples 19 through the upper ends 20 and 21 of which the battery electrodes extend. It will be noted in Fig. 4 that the lower edge of the cap 17 extends straight across the top of the container.

In the form shown in Fig. 5 the cap 17 is provided with a layer 18 of reenforcing material, and nipples 19. In this form, however, the cap is provided on its under surface with a dependent flange 22, as well as a recess 23 on its under surface. This recess is formed for the same purpose as the recess 10 previously mentioned. The cap 17 is also provided with a filling aperture 24 and a vent hole 25.

In the form of the cap 17 shown in Fig. 5 the lower edge of the dependent flange 22 extends straight across without being provided with a recess 23.

The reason why the layer of reenforcing material, such as rubber, is applied or vulcanized to the cap of softer material is to give it the proper stiffness whenever the cap is to be used on the ends of containers of substantial diameter where the liability of a soft cap to sag or bend is greater than with smaller sized containers.

In the general contemplation of the invention, therefore, it can be observed that I provide a cap which is laid on the upper end of the container and held thereon by the engagement therewith of part of a ring

which embraces the upper end of the container, this part preferably being an inwardly extending flange. It will be noted, however, that this flange extends only far enough inwardly to engage the edge of the cap and does not interfere with the area occupied by the nipples, so that the ring can be screwed on tightly against the cap without affecting the position of the nipples. Therefore the closure can be made very tight without the liability of the cap being twisted. The elimination of this liability prevents the parts of the battery connected to the cap from getting out of alignment.

What I claim is:—

1. A battery construction, which comprises a cap of pliable material adapted to be placed across the open end of a battery container and to rest on the upper edge thereof, a dependent flange formed on the under surface of the cap, said flange adapted to provide a shoulder to bear against the inner upper edge of the container to form a tight joint therewith and means engageable with said cap to force the latter into contact with the upper edge of said container.

2. A battery construction, which comprises a cap of pliable material adapted to be placed across the open end of a battery container and to rest on the upper edges thereof, a dependent flange formed on the under surface of the cap, said flange adapted to provide a shoulder to bear against the inner upper edge of the container to form a tight joint therewith, and a layer of stiffer material attached to the cap to reenforce the same.

3. A battery construction, which comprises a cap of pliable material adapted to be placed across the open end of a battery container and to rest on the upper edges thereof, a dependent flange formed on the under surface of the cap, said flange adapted to provide a shoulder to bear against the inner edge of the container to form a tight joint therewith, a layer of stiffer material attached to the cap to reenforce the same, and a plurality of apertured nipples formed on the cap permitting the passage therethrough of the upper ends of the battery electrodes.

4. A battery construction, which comprises a cap of pliable material adapted to be placed across the open end of a battery container and to rest on the upper edges thereof, a dependent flange formed on the under surface of the cap, said flange adapted to provide a shoulder to bear against the inner upper edge of the container to form a tight joint therewith, a layer of stiffer material attached to the cap to reenforce the same, and a plurality of apertured nipples formed on the cap permitting the passage therethrough of the upper ends of the battery electrodes, said cap on its under sur-

face provided with a recess across the area occupied by the nipples whereby leakage of liquid through the joint is substantially eliminated.

5. A storage battery comprising a container having a screw top and containing positive and negative plates having upstanding terminals or posts, a cover composed of a relatively soft member having integral bosses through which the terminals extend and in which they are tightly fitted to form a seal, and a relatively hard member adapted to be screwed onto the top of the container and serving to clamp the relatively soft member onto the container, said member having a central opening through which said bosses and terminals extend.

6. A cover adapted to engage a cell jar comprising a flat portion adapted to engage the top of the jar, an annular portion for engaging the side of the jar, a projection on the flat portion for engaging a post, the projection being integral with the flat portion and comprising material which is more pliable than the flat portion, whereby the projection may frictionally position a post and be the sole means for supporting it within said jar.

7. In combination, a storage cell having one end thereof open and having the exterior portion threaded adjacent said open end, plates within the cell, a cover having a top portion and a flanged portion, the flanged portion being interiorly threaded for engaging the threaded portion of the jar, said cover being sufficiently pliable on the top portion to provide a leak-proof joint with the jar and to be the sole means for positioning the cell plates, and the flanged portion being sufficiently rigid to prevent withdrawal of the cover from the jar without unscrewing the threaded portion.

8. A battery construction, which comprises a container provided with a screw-threaded end portion, a cap of pliable material adapted to be placed across the open end of said container and to rest upon the upper edge thereof, said cap having formed integral therewith a depending flange adapted to bear against the inner upper portion of said container, and a screw-threaded cover member cooperating with the screw-threaded portion of said container and having a portion engageable with said cap to hold the latter rigidly in contact with the upper edge of said container.

PAUL M. MARKO.
